TIP HOLDER AND FEEDER FOR
SEWING MACHINESWilliam Farkas and Isidor Friedman,
Brooklyn, N. Y.

Application April 21, 1942, Serial No. 439,838

9 Claims. (Cl. 112—104)

This invention relates to new and useful improvements in a tip holder and feeder for sewing machines.

More specifically, the invention proposes the construction of a tip holder and feeder characterised by a device for use in connection with a conventionally constructed sewing machine for securing umbrella tip members in position upon the edges of an umbrella cover in a manner to be engageable with the ends of the ribs of the umbrella frame.

Another object of the invention proposes providing the tip holding device with a tip holder rod upon the end of which a conventional tip is adapted to be mounted to be in a position beneath the pressure foot of the sewing machine to be urged into intimate contact with the umbrella cover when the pressure foot is lowered to an operative position.

It is a further object of this invention to provide a means for mounting the tip holder rod on a horizontally slidably supported member in a manner to permit the member to be urged relative to the machine in a manner to project the free end of the rod from beneath the pressure foot of the sewing machine to facilitate the engagement of the tips upon the end of the rod.

For further comprehension of this invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a plan view of a portion of an umbrella having a tip secured to the edge of the cover in accordance with this invention.

Fig. 2 is a front elevational view of the tip holding device shown applied to a conventional sewing machine.

Fig. 3 is a substantially horizontal sectional view taken substantially on the line 3—3 of Fig. 2.

Fig. 4 is a vertical sectional view taken on the line 4—4 of Fig. 3.

Fig. 5 is a horizontal sectional view taken on the line 5—5 of Fig. 2.

Fig. 6 is a view similar to Fig. 2 but illustrating another position of the tip holding device.

Fig. 7 is a perspective view of the tip per se.

Fig. 8 is a longitudinal sectional view of one of the tips illustrated in position upon the end of tip holder rod.

Fig. 9 is a view similar to Fig. 1, but illustrating the tip attached to the umbrella cover in accordance with a modification of this invention.

Fig. 10 is a front view of the tip holding device and conventional sewing machine being used to attach the tip in accordance with the modification shown in Fig. 9.

Fig. 11 is a perspective view of a modified form of tip which may be used in connection with either modification of the invention.

The tip holder and feeder for sewing machines, according to this invention, is to be used to attach the tips 10 at spaced points along the edge of the umbrella cover 11 so as to be engageable with the ends of the ribs 12 of the umbrella frame to secure the umbrella cover 11 to the ribs of the frame. The cover is to be provided with as many tips 10 as the frame has ribs 12 and each of the tips is alike in construction. That is, each tip 10 has a longitudinal inwardly extended opening 13 into which the end of the rib 12 is adapted to be projected, and a transverse passage 14 through which the stitches pass. In this first form of the invention the tips 10 are secured to the umbrella cover with their longitudinal openings 13 directed radially outwards, (see Fig. 2) and the edge of the cover is thereafter bent under to permit the ends of the radially extending ribs of the umbrella frame to be engaged into the openings 13 in the tips.

The tip holding device is to be used in combination with a conventionally constructed sewing machine 15, illustrated on the drawings without its needle shifting mechanism, having a base 16 which is secured in position upon the face of a table top 17. The base also is adapted to have the umbrella cover 11 to which the tips 10 are to be engaged, rested thereon. The sewing machine 15 further includes a frame 18 which overhangs a portion of the base 16. The frame 18 supports a pressure foot 19 which may be raised from the operative position shown in Fig. 2 to the inoperative position shown in Fig. 6. The frame 18 further supports a sewing needle 20.

The frame 18 of the sewing machine 15 further supports and carries a hopper 21 which is designed to feed the tips 10 from a supply in a manner to be conveniently engaged upon the tip holding device as will be hereinafter described. The hopper 21 is characterized by a container 22 securely but removably mounted upon the front portion of the frame 18. The container 22 has an open top 23 through which the supply of tips within the container may be easily replenished. The bottom of the container 22 is formed with a discharge opening 24 arranged in close proximity to the pressure foot of the sewing machine and through which the tips 10 are to be ejected from the hopper 21 one at a time, by pressing on the head 24a of an ejecting plunger 24b which is held in an inoperative condition by a coil spring 24c.

The tip holding device is characterized by a bracket 25 which is located at a point, spaced slightly laterally of the end of the sewing machine base 16, and upon the top face of the table 17. The bracket is secured in position by means of several screws 26 which pass freely through the

bracket 25 and threadedly engage the table top 17.

An arm 27 is pivotally supported upon the bracket 25 and projects upwards and laterally thereof. The arm 27 has its bottom end engaged between a pair of upwardly extending lugs 28 formed on the bracket 25.

A shoulder screw 29 is engaged through the overlapped portions of the lugs 28 and the end of the arm 27 for pivotally supporting the arm upon the bracket 25.

A member 30 is mounted horizontally upon the top end of the arm 27. The member 30 is slidably but non-rotatively mounted upon the top end of the arm 27 and is adapted to move laterally of the machine 15. The member 30 is disposed between the arms of a bifurcated end 31 formed upon the top end of the arm 27. A square stud 32 is extended between the arms of the bifurcated end 31 and passes through an elongated slot 33 formed in the end of the member 30. The top and bottom faces of the square stud 32 are in intimate contact with the faces of the member 30 defining the slot 33. This intimate contact limits relative rotation between the stud 32 and the member 30 but permits the member to be moved laterally of the stud.

The member 30 supports a tip holder rod 34. The end of the tip holder rod 34 is adapted to be engaged into the longitudinal opening 13 of the tip 10 as shown in Fig. 8. When the tip 10 is in position upon the end of the rod 34 the pressure foot may be urged downwards to move the tip and tip holder rod 34 downwards into a position in which the tip will be in intimate contact with the cover 11 with its passage 14 directed upwards and in alignment with the needle 20. This position is clearly illustrated in Fig. 2.

The other end 35 of the tip holder rod 34 is enlarged and is slidably extended into a complementary opening 36 formed in the end of the member 30. A set screw 37 is threadedly engaged through the side of the member 30 and engages the enlarged end 35 of the tip holder rod 34 to fixedly hold the rod 34 in various extended positions. This adjustment is provided to permit the position of the tip 10 when in position on the end of the tip holder 34 to be adjusted to align its passage 14 with the needle 20.

Resilient means is provided for urging the arm 27 and the horizontal member 30 and the tip holder rod 34 into a normal position in which a tip 10 mounted upon the end of the tip holder rod 34 will be slightly above the base 16 of the sewing machine when the pressure foot 19 is raised. This position is illustrated in Fig. 6.

The first of these resilient means is provided for urging the arm 27 laterally with relation to the bracket 25. This means is characterized by a coil spring 38 mounted in an opening 39 formed in one of the lugs 28. The spring 38 and opening 39 encircle the end of the screw 29 which rotatively supports the arm. The spring 38 has one of its ends connected with the bottom end of the arm 27 and its other end connected with the lug 28. This spring 38 exerts a force sufficiently great to pivot the arm 27 and the elements it carries relative to the bracket but a force less than the force exerted by the pressure foot 19 so that when the pressure foot 19 is moved downwards, its downward force will be capable of pivoting the arm 27 relative to the bracket 25 to engage the tip 10 against the umbrella cover 11 resting upon the base 16 of the machine 15.

The other resilient means is characterized by

an expansion spring 40 which operates between the square stud 32 and the end of the slot 33 for urging the member 30 laterally outwards relative to the arm 27. A projection 41 extends from the end wall of the slot 33 and projects into the open end of the spring 40 for holding the end of the spring 40 in position in the end of the slot 33.

Means is provided for limiting pivoting of the arm 27 relative to the bracket 25. This means is characterized by a lug 42 which projects from the bracket 25 and which extends upwards along side of the arm 27. A set screw 43 is threadedly engaged through the lug 42 and is adapted to engage the side of the arm 27 in the normal position of the arm shown in Fig. 6.

As shown in Fig. 5 the inner faces of the arms of the bifurcated end 31 of the arm 27 converge inwardly and only touch the member 30 at the sides of the stud 32. This permits slight sidewise movement of the member 30 relative to the arm 27, and is for the purpose of preventing the needle 20 or the tip 10 from being broken in the event the needle should come down with the passage 14 of the tip improperly aligned with the needle 20. If this should happen the needle 20 will merely ride across the curved face of the tip and urge the tip 10, the tip holder rod 34 and the member 30 slightly sidewise about the converging sides of the arms of the bifurcated end 31 as a pivot and pass the tip 10 by.

The operation of this form of the invention is as follows:

Assuming the machine is in the position illustrated in Fig. 2. The needle 20 is reciprocated and oscillated to and fro and will engage through the passage 14 and through the material of the cover 11 on either side of the tip 10 to securely attach the tip to the cover. After the sewing operation is completed the thread is severed and the pressure foot 19 is raised. The end of the tip holder rod 34 is then disengaged from the opening 13 in the tip and the spring 28 will pivot the arm 27 to cause the end of the tip holder rod 34 to assume the position shown in full lines in Fig. 6. The device is now ready to receive the next tip 10. Another tip 10 is manually removed from the hopper 21 and is manually engaged upon the end of the tip holder rod 34 with its passage 14 directed upwardly by passing the end of the rod 34 into the opening 13.

To continue the application of the tips 10 to the cover 11, the next spot on the cover to which a tip is to be applied is brought into position beneath the pressure foot. The pressure foot is then lowered and pivots the arm 27 about the screw 29 against the holding action of the spring 38 to engage the tip 10 on the face of the cover 11 and the sewing operation is repeated.

To engage new tips 10 upon the end of the tip holder rod in the normal raised position of the rod, the member 30 may be moved manually laterally inwards relative to the stud 32 and against the holding action of the spring 40 as indicated by the dot and dash line 30' in Fig. 6. This causes the free end of the tip holder rod 34 to be extended from beneath the pressure foot as indicated by the dot and dash lines 34' in Fig. 6 to permit the tip 10 to be more easily manually properly engaged upon the end of the rod 34 with its passage 14 extended vertically.

In the modification of the invention illustrated in Figs. 9 and 10, provision is made for attaching the tip 10 to the cloth cover 11 of the umbrella with its longitudinal opening 13 directed

radially inwards to be engageable more easily with the end of the rib of the umbrella frame. To accomplish this the umbrella cover 11 is disposed upon the base 16 of the sewing machine 15 to extend laterally outwards of the machine, as shown in Fig. 10.

In other respects this form of the invention is similar to that previously described and like letters of reference are used to denote like parts in each of the several views.

In Fig. 11 a modified type of tip is illustrated for use in connection with a tip holder constructed in accordance with this invention. This modified tip 10' is formed with longitudinal openings 13' which extend inwards from each of its ends. Between the ends of the openings 13' the tip 10' is formed with a reduced area 14' across which the stitches are adapted to be engaged for securely attaching the tip 10' to the umbrella cover. The openings 13' permitting the end of the rib of the umbrella frame to be engaged into one, and a decorative tip member (not shown on the drawings) of any desired design, to be engaged into the other.

It is to be understood that the hopper 21 may be interchangeable so that tips of different color or design may be supplied for the umbrellas by merely interchanging the hoppers, containing the desired tips.

While we have illustrated and described the preferred embodiments of our invention, it is to be understood that we do not limit ourselves to the precise constructions herein disclosed and the right is reserved to all changes and modifications coming within the scope of the invention as defined in the appended claims.

Having thus described our invention what we claim as new and desire to secure by United States Letters Patent is:

1. In combination with a sewing machine having a pressure foot which may be raised to an inoperative position and also having a sewing needle, a bracket for attachment to a stationary object located laterally of and at a specific distance from said sewing machine, an arm pivotally mounted on said bracket and projecting upwards and laterally thereof, a substantially horizontal member slidably and non-rotatively mounted on said arm and extending towards said sewing machine, a tip holder rod mounted on said member for holding a tip beneath said pressure foot, resilient means urging said arm and horizontal member and tip holder into a normal position in which a tip on said holder will be slightly above the bed of the sewing machine when said pressure foot is raised, and resilient means urging said horizontal member and tip holder rod relative to said arm and into a position in which the free end of said tip holder rod will be in sewing position below said pressure foot when the same is lowered to an operative position.

2. In combination with a sewing machine having a pressure foot which may be raised to an inoperative position and also having a sewing needle, a bracket for attachment to a stationary object located laterally of and at a specific distance from said sewing machine, an arm pivotally mounted on said bracket and projecting upwards and laterally thereof, a substantially horizontal member slidably and non-rotatively mounted on said arm and extending towards said sewing machine, a tip holder rod mounted on said member for holding a tip beneath said pressure foot, resilient means urging said arm and horizontal member and tip holder into a normal position in which

a tip on said holder will be slightly above the bed of the sewing machine when said pressure foot is raised, resilient means urging said horizontal member and tip holder rod relative to said arm and into a position in which the free end of said tip holder rod will be in sewing position below said pressure foot when the same is lowered to an operative position, said pivotal mounting of said arm comprising spaced upwardly extending lugs 10 formed on said bracket and between which the bottom end of said arm is disposed, and a screw engaged through the overlapped portions of said arm and lugs.

3. In combination with a sewing machine having a pressure foot which may be raised to an inoperative position and also having a sewing needle, a bracket for attachment to a stationary object located laterally of and at a specific distance from said sewing machine, an arm pivotally mounted on said bracket and projecting upwards and laterally thereof, a substantially horizontal member slidably and non-rotatively mounted on said arm and extending towards said sewing machine, a tip holder rod mounted on said member for holding a tip beneath said pressure foot, resilient means urging said arm and horizontal member and tip holder into a normal position in which a tip on said holder will be slightly above the bed of the sewing machine when said pressure foot is raised, resilient means urging said horizontal member and tip holder rod relative to said arm and into a position in which the free end of said tip holder rod will be in sewing position below said pressure foot when the same is lowered to an operative position, said pivotal mounting of said member comprising a bifurcated top end formed on said arm and between the arms of which said member is disposed, a square stud extended between the arms of said bifurcated end and passing through an elongated slot formed in said member.

4. In combination with a sewing machine having a pressure foot which may be raised to an inoperative position and also having a sewing needle, a bracket for attachment to a stationary object located laterally of and at a specific distance from said sewing machine, an arm pivotally mounted on said bracket and projecting upwards and laterally thereof, a substantially horizontal member slidably and non-rotatively mounted on said arm and extending towards said sewing machine, a tip holder rod mounted on said member for holding a tip beneath said pressure foot, resilient means urging said arm and horizontal member and tip holder into a normal position in which a tip on said holder will be slightly above the bed of the sewing machine when said pressure foot is raised, resilient means urging said horizontal member and tip holder rod relative to said arm and into a position in which the free end of said tip holder rod will be in sewing position below said pressure foot when the same is lowered to an operative position, said tip holder rod having one of its ends enlarged and extended into a complementary opening formed in the end of said member, and a set screw mounted through said member and engaging the side of said enlarged portion of said tip holder rod comprising the mounting of said rod on said member.

5. In combination with a sewing machine having a pressure foot which may be raised to an inoperative position and also having a sewing needle, a bracket for attachment to a stationary object located laterally of and at a specific distance from said sewing machine, an arm pivotally

mounted on said bracket and projecting upwards and laterally thereof, a substantially horizontal member slidably and non-rotatively mounted on said arm and extending towards said sewing machine, a tip holder rod mounted on said member for holding a tip beneath said pressure foot, resilient means urging said arm and horizontal member and tip holder into a normal position in which a tip on said holder will be slightly above the bed of the sewing machine when said pressure foot is raised, resilient means urging said horizontal member and tip holder rod relative to said arm and into a position in which the free end of said tip holder rod will be in sewing position below said pressure foot when the same is lowered to an operative position, said slidable mounting of said member, comprising a bifurcated top end formed on said arm and between the arms of which said member is disposed, a square stud extended between the arms of said bifurcated end and passing through an elongated slot formed in said member, said second-named resilient means urging said horizontal member, comprising an expansion spring operating between said stud and the end of said slot.

6. In combination with a sewing machine having a pressure foot which may be raised to an inoperative position and also having a sewing needle, a bracket for attachment to a stationary object located laterally of and at a specific distance from said sewing machine, an arm pivotally mounted on said bracket and projecting upwards and laterally thereof, a substantially horizontal member slidably and non-rotatively mounted on said arm and extending towards said sewing machine, a tip holder rod mounted on said member for holding a tip beneath said pressure foot, resilient means urging said arm and horizontal member and tip holder into a normal position in which a tip on said holder will be slightly above the bed of the sewing machine when said pressure foot is raised, resilient means urging said horizontal member and tip holder rod relative to said arm and into a position in which the free end of said tip holder rod will be in sewing position below said pressure foot when the same is lowered to an operative position, said slidable mounting of said member, comprising a bifurcated top end formed on said arm and between the arms of which said member is disposed, a square stud extended between the arms of said bifurcated end and passing through an elongated slot formed in said member, said second-named resilient means urging said horizontal member, comprising an expansion spring operating between said stud and the material of said member at one end of said slot, said member being formed with a projection extended into the adjacent end of said spring for holding said spring in position within said slot.

7. In combination with a sewing machine having a pressure foot which may be raised to an inoperative position and also having a sewing needle, a bracket for attachment to a stationary object located laterally of and at a specific distance from said sewing machine, an arm pivotally mounted on said bracket and projecting upwards and laterally thereof, a substantially horizontal member slidably and non-rotatively mounted on said arm and extending towards said sewing machine, a tip holder rod mounted on said member for holding a tip beneath said pressure foot, resilient means urging said arm and horizontal member and tip holder into a normal position in which a tip on said holder will be slightly above

the bed of the sewing machine when said pressure foot is raised, resilient means urging said horizontal member and tip holder rod relative to said arm and into a position in which the free end of said tip holder rod will be in sewing position below said pressure foot when the same is lowered to an operative position said pivotal mounting of said arm comprising spaced upwardly extending lugs formed on said bracket and between which the bottom end of said arm is disposed, and a screw engaged through the overlapped portions of said arm and lugs, said first-named resilient means urging said arm relative to said bracket, comprising a coil spring mounted concentrically of said screw within an opening formed in one of said lugs and having one of its ends connected to said arm and its other end connected to said lug.

8. In combination with a sewing machine having a pressure foot which may be raised to an inoperative position and also having a sewing needle, a bracket for attachment to a stationary object located laterally of and at a specific distance from said sewing machine, an arm pivotally mounted on said bracket and projecting upwards and laterally thereof, a substantially horizontal member slidably and non-rotatively mounted on said arm and extending towards said sewing machine, a tip holder rod mounted on said member for holding a tip beneath said pressure foot, resilient means urging said arm and horizontal member and tip holder into a normal position in which a tip on said holder will be slightly above the bed of the sewing machine when said pressure foot is raised, resilient means urging said horizontal member and tip holder rod relative to said arm and into a position in which the free end of said tip holder rod will be in sewing position below said pressure foot when the same is lowered to an operative position, and means limiting lateral outward pivoting of said arm relative to said bracket.

9. In combination with a sewing machine having a pressure foot which may be raised to an inoperative position and also having a sewing needle, a bracket for attachment to a stationary object located laterally of and at a specific distance from said sewing machine, an arm pivotally mounted on said bracket and projecting upwards and laterally thereof, a substantially horizontal member slidably and non-rotatively mounted on said arm and extending towards said sewing machine, a tip holder rod mounted on said member for holding a tip beneath said pressure foot, resilient means urging said arm and horizontal member and tip holder into a normal position in which a tip on said holder will be slightly above the bed of the sewing machine when said pressure foot is raised, resilient means urging said horizontal member and tip holder rod relative to said arm and into a position in which the free end of said tip holder rod will be in sewing position below said pressure foot when the same is lowered to an operative position, said slidable mounting of said member, comprising a bifurcated top and end formed on said arm and between the arms of which said member is disposed, a square stud extended between the arms of said bifurcated end and passing through an elongated slot formed in said member, said arms of said bifurcated end having their inner faces converging permitting sidewise pivoting of said member relative to said arm.

WILLIAM FARKAS.
ISIDOR FRIEDMAN.
